UNITED STATES PATENT OFFICE.

HARRY L. VAUGHAN, OF CHICAGO, ILLINOIS.

DESIGN FOR A BOTTLE-CAP REMOVER.

42,070.

Specification for Design.

Patented Dec. 26, 1911.

Application filed January 17, 1911. Serial No. 603,190. Term of patent 7 years.

To all whom it may concern:

Be it known that I, HARRY L. VAUGHAN, citizen of the United States, residing at Chicago, in the county of Cook and State of Illinois, have invented a new, original, and ornamental Design for Bottle-Cap Removers, of which the following is a specification.

This invention relates to an improvement in a new and ornamental design for a bottle cap remover of the type illustrated in the accompanying drawings, in which the figure

is a plan view of a device embodying my design.

I claim—

The ornamental design for a bottle cap remover as shown.

In testimony whereof I affix my signature in presence of two witnesses.

HARRY L. VAUGHAN.
